Primary Examiner — Austin Murphy(74) *Attorney, Agent, or Firm* — Lowe Graham Jones PLLC(57) **CLAIM**

I claim the ornamental design for the collapsible dish drainer, as shown.

DESCRIPTION

FIG. 1 is a perspective view of the collapsible dish drainer, showing my new design.

FIG. 2 is a top view of the collapsible dish drainer.

FIG. 3 is a front view of the collapsible dish drainer.

FIG. 4 is a right side view of the collapsible dish drainer.

FIG. 5 is a left side view of the collapsible dish drainer.

FIG. 6 is a rear view of the collapsible dish drainer; and,

FIG. 7 is a bottom view of the collapsible dish drainer.

1 Claim, 6 Drawing Sheets(56)
